UNITED STATES PATENT OFFICE.

LEE R. TROMPETER, OF CEDAR RAPIDS, NEBRASKA.

OPERATING TABLE.

Application filed June 21, 1922. Serial No. 569,906.

To all whom it may concern:

Be it known that I, LEE R. TROMPETER, a citizen of the United States, residing at Cedar Rapids, in the county of Boone and State of Nebraska, have invented certain new and useful Improvements in Operating Tables, of which the following is a specification.

This invention has for its object the provision of an easily adjusted and efficient table especially adapted for holding hogs and other domestic animals while they are being vaccinated or being subjected to other surgical operations. The invention seeks to provide a table which may be readily adjusted to the position most suitable under any given circumstances and which, when not in use, may be collapsed into a very compact form so that it may be stored in a small space. Other incidental objects of the invention will appear in the course of the following description.

The invention is illustrated in the accompanying drawings and will be hereinafter fully set forth.

In the said drawings—

Figure 1 is a side elevation of one embodiment of my invention showing the same arranged to support the table top in a flat horizontal position;

Fig. 2 is an end view thereof;

Fig. 3 is a side view showing the table top partly folded so as to assume a trough-like form;

Fig. 4 is a transverse section on line 4—4 of Fig. 3;

Fig. 5 is a side elevation showing the table top arranged as shown in Figs. 3 and 4 but inclined instead of horizontal;

Figs. 6 and 7 are views of the supporting structure in collapsed condition;

Fig. 8 is a bottom plan view of the table top showing the same as it appears when opened;

Fig. 9 is an edge view of the same;

Fig. 10 is a detail horizontal section on the line 10—10 of Fig. 2;

Fig. 11 is an enlarged detail sectional elevation of a portion of one of the legs.

In carrying out my invention, I employ a plurality of supporting legs which are preferably arranged in rectangular relation and each of which consists of a lower standard 1 having an enlarged foot 2 at its lower end which is preferably of spherical formation, as shown, in order to readily move it from

place to place as may be desired. This said standard 1 fits slidably and telescopically within an upper tubular section 3 and the members 1 and 3 are held in any set relative position by a set screw 4 mounted in the lower end of the tubular member 3 and adapted to bear against the standard 1, as shown clearly in Fig. 11, the lower end of the tubular member being annularly enlarged, as shown at 5, to provide a sufficient bearing for the set screw and also to serve as a stop for a sliding collar which will presently be more particularly mentioned. The upper end of the tubular member 3 is provided with an enlarged spherical head 6 which imparts a somewhat ornamental appearance to the table, and upon the said member immediately below the said head, I secure collars 7 and 8 by set screws 9, as shown and as will be readily understood. These collars 7 and 8 are each provided with laterally projected lugs or ears 10 to which braces are pivotally attached. Collars or sleeves 11 are slidably mounted upon the upper outer hollow members 3 below the centers thereof and diagonally disposed braces 12 are pivoted at their lower ends to the lugs or ears 13 on the said collars or sleeves 11 and at their upper ends to the lugs or ears 10 on the lower collars 8. These braces 12 cross each other, as shown clearly in Figs. 2 and 4, and are provided with longitudinal series of openings 14 therethrough through which set bolts or pins 15 may be inserted to secure the braces against relative movement. Upon reference to Figs. 2 and 4, it will be noted that the legs may be held in vertical positions or may be disposed so as to converge upwardly and will be held against spreading in either position by the said braces 12. Extending between the upper collars 7 at the ends of the table are foldable braces 16 which have their outer ends detachably pivoted to the lugs 10 upon the said collars by thumb screws 17 and have their inner ends connected by a rule joint 18 whereby the brace may be folded in one direction but will be held against movement in the opposite direction. When the table top is to be supported in a flat horizontal position, as shown in Figs. 1 and 2, the braces 16 are arranged with their stop shoulders 19 at their top sides so that the braces will be prevented from folding downwardly, but if the table top is to be supported in a trough-like form, as shown in Figs. 3 and 4, the thumb

screws 17 are removed, the braces are reversed and the thumb screws then replaced so that the braces may be folded downwardly, as shown in Fig. 4. I also provide 5 collars 20 which are secured to the tubular members 3 by set screws 21, these collars 20 being arranged above the sleeves or collars 11 and being provided with laterally projecting lugs 22 and 23. By referring more 10 particularly to Fig. 10, it will be noted that the lugs 23 are substantially parallel to the lugs 13 and adjacent the same, while the lugs 22 are disposed at a right angle to the lugs 13 and 23. Pivoted to the lugs 23 and extending 15 between the same at the ends of the table are folding braces 24 which correspond in construction to the braces 16 but are arranged to fold or break upwardly only. When the table top is used in a flat condition, as shown 20 in Figs. 1 and 2, the braces 24 will be folded upwardly, but when the table top is used in the V-shaped form, shown in Figs. 3 and 4, and the legs are converged upwardly, the braces 24 are straightened, as shown in Fig. 25 4, so that spreading of the legs and collapse of the structure will be prevented. The folding braces cooperate with the diagonally disposed braces 12 and impart rigidity to the structure so that it will be very firm while 30 in use.

Slidably mounted upon the tubular members 3 of the legs above the collars 20 are the sleeves or collars 25, the downward movement of which is limited by lugs or 35 other forms of stops 26 upon the said members. These sleeves or collars 25 are provided with lugs or ears 27 corresponding in location to the lugs 22 upon the collars 20, and pivotally attached to the said lugs 22 and 27 are the outermost members of lazy 40 tongs 28 which extend along the sides of the table and are pivotally attached to sleeves and collars at each end thereof. When the table is to be used, the lazy tongs are opened 45 or extended, as shown in Figs. 1, 3 and 5, so that the legs may be moved apart to the full length of the table top, but when the device is not in use, the lazy tongs is collapsed, as shown in Fig. 6, so that the legs will be 50 brought close together with the lazy tongs folded between them and the device may be then placed out of the way in a corner or other small space. When the device is to be thus folded, the braces 16 and 24 are, of 55 course, broken or folded, as shown in Fig. 7, and the rigid braces 12 are, of course, permitted to swing into positions closely approaching parallelism.

The table top consists of two leaves or 60 sections 29 which are similar in construction and are connected at their inner meeting edges by hinges 30, the hinges being secured to the under sides of the sections or leaves and having their pivot pins disposed 65 between the meeting edges of the leaves in

recesses or notches provided therefor. The table top may thus be opened into a flat position, as shown in Fig. 2, or may be folded together so as to assume a trough-like or V-shaped form, as shown in Fig. 4, or may have their working surfaces brought against each other so as to occupy the minimum space when the device is not in use. The outer longitudinal edges of the sections 29 are reinforced by angle irons 31 having notches 32 in the edges of their depending webs adapted to engage the braces 16 at the opposite ends of the supporting structure. The table top will thus be carried by the 70 said braces and will be prevented from having endwise movement, and it will be readily noted that the top is not fastened to the braces so that, while it will not shift in use, it may be removed by simply lifting it from the braces. Near the inner meeting edges of 75 the leaves 29 and alined with the notches 32 in the braces 31 are brackets 33 having depending webs provided with notches 34 which are also adapted to engage over the braces 16 and thereby aid in maintaining the table top in the operative position. It is frequently necessary to bind the animal upon the table so as to hold him in proper position for a successful operation, and to 80 accomplish this end I provide the chains 35 which may be carried over the table top, as shown clearly in Figs. 3, 4 and 5, and engaged in hook bolts 36 provided in the legs near the upper ends thereof. These hook 85 bolts are inserted diametrically through the upper members 3 of the legs and are held in such position as to prevent slipping of the chains by thumb nuts 37 mounted upon the threaded ends of the bolts and turned 90 home against the legs, as shown and as will 95 be readily understood.

From the foregoing description, taken in connection with the accompanying drawings, it will be seen that I have provided a very simple and easily adjusted table which 100 will be held firmly in its operative position when it is in use and may be very easily and quickly folded into a small compass when it is to be stored out of the away. When setting up the device, it is necessary 110 merely to move the legs apart to the extent permitted by the lazy tongs at the sides and the braces at the ends. When the legs are in the collapsed adjustment shown in Figs. 6 and 7, the upper folding braces are, of 115 course, arranged in the position shown in Fig. 4. If it be desired to support the table top in flat form, as shown in Fig. 2, the said braces 16 are removed and reversed so as to bring their stop shoulders 19 to the top, after which the ends of the braces are fitted 120 to the lugs 10 and secured by the thumb screws 17. The table top is then merely opened and placed upon the braces and if 125 the use of the chains 35 is necessary, they 130

are secured over the body of the animal after the animal has been placed upon the table. When the legs have been moved apart to the desired positions, the pins or bolts 15 are inserted through alined openings 14 in the braces 12 so that lateral collapse of the structure will be prevented, and endwise collapse will obviously be prevented by the engagement of the braces 16 with the end walls of the notches 36 and 34 in the reinforcing bars 31 and the brackets 33 respectively. The telescopic form of the legs permits the table top to be brought to any desired height quickly and easily and also enables the operator to support the table top in an inclined position, as shown in Fig. 5. The enlargements or collars 5 serve as stops to limit the downward movement of the sleeves or collars 11 when the supporting structure is being folded, and the collars 20 serve as stops for the collars or sleeves 11 when the structure is being set up. Spreading of the legs longitudinally is prevented not only by the engagement of the braces 16 with the notches 32 and 34 but is also prevented by the engagement of the collars or sleeves 25 with the stops 26 inasmuch as separation of the legs endwise of the table involves longitudinal or horizontal extension of the lazy tongs and this extension of the lazy tongs is prevented by the stops 26 arresting the downward movement of the collars or sleeves 25.

Having thus described the invention, what is claimed as new is:

1. A table comprising a plurality of legs arranged in rectangular relation, foldable means connecting the legs longitudinally, means connecting the legs transversely and securing them in vertical or in upwardly converging positions, and a foldable top fitting between the upper ends of the legs and

constructed on its under side to engage the upper transverse connecting means in either position of the legs and thereby prevent collapse of the longitudinal connecting means. 45

2. A table comprising a plurality of legs arranged in rectangular relation, lazy tongs connecting said legs in pairs, longitudinally foldable braces connecting the legs in pairs 50 transversely, crossed braces connecting the legs transversely in pairs, an adjustable connection between the crossed braces whereby the legs may be held in vertical positions or may converge upwardly, the folding braces 55 being reversible, and a foldable table top constructed to rest upon and engage the foldable braces and by its engagement with the foldable braces prevent extension of the lazy tongs. 60

3. A table comprising a plurality of legs arranged in rectangular relation, crossed braces connecting the legs transversely in pairs, an adjustable connection between said crossed braces, reversely arranged upper and lower foldable braces connecting the legs in pairs transversely whereby the legs may be held in vertical positions or may be held in upwardly converging positions, lazy tongs 65 connecting the legs in pairs longitudinally, 70 and a table top constructed to rest upon and engage the upper foldable braces.

4. A table comprising a plurality of legs arranged in rectangular relation, foldable means for connecting the legs longitudinally 75 and transversely, said means including transversely disposed braces at the upper ends of the legs, and a table top provided on its under side with depending webs having notches in their lower edges to engage 80 the said braces.

In testimony whereof I affix my signature.

LEE R. TROMPETER. [L. s.]
